UNITED STATES PATENT OFFICE.

ELIAS RATNER, OF NEW YORK, N. Y., ASSIGNOR OF ONE-HALF TO ABRAHAM J. RATNER, OF NEW YORK, N. Y.

ELECTRIC SWITCH.

Application filed April 2, 1924. Serial No. 703,692.

The present invention relates to electric switches and is more particularly directed toward a pull-chain switch suitable for use as a socket switch.

5 The present invention contemplates a switch structure which may be made sufficiently compact so that it may be inserted into a standard sized socket shell after it has been assembled. It also contemplates a 10 switch structure made out of a small number of easily made parts so designed as to facilitate the assembly of the switch.

The construction is such that sufficiently large contacts and conductors may be employed, and hence the switch is well suited for use in controlling comparatively heavy currents. The present invention provides a socket switch capable of safely and satisfactorily controlling 660 watts.

20 Among the objects of the present invention are the provision of a switch having an improved form of insulating body, improved fixed and movable contacts, an improved arrangement of connections, simple operating mechanism, improved devices for connecting and for guiding the pull chain, and an improved mode of coupling the insulating parts together with the switch mechanism enclosed thereby.

25 Another object of the present invention is to provide parts so designed that metal parts may be formed out of sheet metal, and insulating parts may be moulded out of insulating material.

30 Other and further objects of the present invention will appear as the illustrative embodiment is described.

The drawings show for purposes of illustrating the invention, one of the many possible embodiments in which the present invention may take form, it being understood that the drawings are merely illustrative of the invention which may be embodied in various forms.

35 In these drawings:

Fig. 1 is a vertical sectional view through the socket switch taken on the line 1—1 of Figures 2 to 5 inclusive, showing the switch operating mechanism in an intermediate position;

Fig. 2 is a vertical section taken on the line 2—2 of Fig. 1 looking toward the left;

Fig. 3 is a vertical section taken on the

line 3—3 of Fig. 1 looking toward the right;

Fig. 4 is a vertical section taken on the line 4—4 of Fig. 1 looking toward the left;

Fig. 5 is a horizontal section taken on the line 5—5 of Figs. 1 to 4 inclusive showing the switch operating mechanism in one extreme position;

Fig. 6 is a vertical section showing fragments of construction and taken on the line 6—6 of Fig. 8;

Fig. 7 is a vertical section showing fragments of construction and taken on the line 7—7 of Fig. 9;

Figs. 8 and 9 are elevational views showing the binding posts and external contacts;

Fig. 10 is a perspective view illustrating the assembling of the insulating elements of the switch;

Fig. 11 is a perspective view illustrating the assembling of the horn for the pull chain on one of the insulating elements;

Fig. 12 shows three views of the movable contact or bridging member and operating ratchet wheel, the wiping surfaces of the bridging member being omitted from one of said views.

Fig. 13 shows three views of a rocking operating member for actuating the movable contact member;

Fig. 14 is a section taken on the line 14—14 of Fig. 13;

Fig. 15 shows two views of the pawl; and

Figs. 16 and 17 are sectional and side elevational views of a pull chain horn.

The socket switch shown in the drawings for purposes of illustrating the invention has a more or less conventional outer metal shell 20 insulating shell 21 and threaded socket contact 22. For convenience the invention will be described by reference to a socket switch although it is of course obvious that many features of the device are susceptible of use in other types of switch.

An insulating body 23 is disposed in the upper end of the shell and this body encloses the switching mechanism. The body is made up by assembling two L-shaped elements 24 and 25 in the manner indicated in Figure 10. The general configuration of these elements is the same. They have circular disk-like end walls 26 and 27, and semi-cylindrical prismatic portions 28 and 29 which extend from the side of the respective end walls.

The external shape of these parts is here determined by the shell structure into which they are inserted.

The insulating element 24 carries the fixed contacts 30 and 31 of the switch in a recess 32 in the inner face 33 of the prismatic portion 28. These contacts are shown as being arc-shaped, and are preferably provided with concaved areas or recesses 34 and 35. The upper contact 30 is fastened in a recess 36 and a screw 37 connects it to a plate 38 carrying a binding screw 39. These screws and the plate are in a recess 40 of suitable size to facilitate the coupling of a lead wire. The lower fixed contact 31 is connected by a screw 31' to a central contact 31'' adapted to cooperate with the center contact of a plug threaded into the socket 22.

The other insulating element 25 has a recess or groove 41 on its outer surface and a conducting strip 42 is mounted therein. The upper end of this strip is anchored by a screw 43, and is provided with a binding screw 44, while the lower end extends across the lower face of the insulating element as shown in Figure 9 where it may be connected with the socket 22 by a screw 45 which passes through the socket and an aperture in the end wall of the other insulating member. The element 25 is recessed at 46 on the inner face 47 of the semi-cylindrical portion 29 thereof in about the same manner as the other insulating element.

When the two insulating elements 23 and 24 are assembled as indicated in Figure 10, the end wall of one element is fitted over the end of the prismatic portion of the other element and the recesses 32 and 46 form a chamber 48 (clearly shown in Figures 1 and 5) for the movable contact and operating mechanism to be described.

The insulating element 24 is provided with a bearing hole 49, centrally located between the fixed contacts 30 and 31, and preferably extending part way through the element, while the other insulating element is provided with a bearing hole 50 directly opposite. These bearing holes are adapted to hold a shaft 51, preferably of steel, and on this shaft the movable parts of the mechanism are mounted.

The movable contact, shown more clearly in Figures 1 and 12 is in the form of a U-shaped bridging member 52 whose ends 53 and 54 are outwardly directed and provided with offset obliquely disposed wiping surfaces 55 and 56 adapted to fit into the concaved areas 34 and 35 of the fixed contacts. This bridging member may be a sheet metal stamping. The bottom 57 of the U is apertured at 58 and outwardly directed prongs 59 attach the metallic bridging member to a ratchet wheel 60, made of insulating material and having a bearing hole 61 to mount the ratchet wheel and contact on the shaft 51.

The operating device for the movable contact, (shown in Figures 1, 3, 4, 5, 13, and 14) is in the form of a sheet metal stamping or body 62 apertured at 63 so as to be pivoted on the shaft 51 and is provided with a pawl 64 cooperable with the ratchet wheel 60. The pawl is pivotally supported between the body of the stamping and a spaced portion 65 formed by folding the margin of the sheet up and over as shown at 66 and 67. This pawl is spring pressed toward the ratchet wheel by a spring 68 wound about the pawl pivot 64' and anchored against a prong or lug 69 struck out of the stamping. This device is to be oscillated and thereby actuate the movable contact. A convenient mechanism for accomplishing this operation is a pull chain, and the drawings show the same.

A pull chain may be conveniently mounted on the stamping 62, by extending the material between the folding lines 66 and 67 out beyond the spaced portion 65, and bending it somewhat as shown at 70, a slot 71 being provided to insert one of the connectors of the pull chain 72. Other prongs 73, 74 and 75 extending outwardly from the body of the stamping 62 act as guides for the pull chain and keep it away from the contact and pawl mechanism.

A return spring 76 is coiled about the shaft 51 and has one end 77 anchored in a hole 78 in the insulating member 25, while the other end 79 is held behind a lug 80 struck out of the stamping 62. To permit the use of a larger spring, there is provided an annular recess 81 about the shaft 51. This spring tends to restore the operating member and pawl to the position from which they were pulled by the chain. This spring also urges the operating member 62, and movable contact 52 together with an interposed washer 82 to the left so as to hold the oblique wiping surfaces 55 and 56 of the movable contacts in the concaved areas 34 and 35 of the fixed contacts 30 and 31, or in similar concaved areas 34' and 35' in the recess 32.

An external guide for the pull chain (shown in Figures 3, 11, 16, and 17) is provided in the form of a horn 83 made up from a tubular conduit member 84 and a sheet metal attaching member 85 having oppositely extending members 86 and 87 whose free ends are folded as shown to form hooked ends 88 and 90.

The insulating members 24 and 25 are provided with lateral concavities or cut-away portions 91 and 92 leading from the recesses 32 and 46 respectively. These cut-away portions provide a channel 93 for the pull chain as shown in Figures 3 and 10. One member of the insulating body, here shown as the member 25, is provided with lateral recesses 94 and 95 on opposite sides of the cut-away portion 92, spaced so as to receive

the hooked ends 89 and 90 of the chain horn. These parts are assembled as shown in Figure 11, the channel 93 being in line with the horn 83, and the edges covered by the stamping 85.

In assembling the switch structure, the various conducting strips, contacts, and binding posts are assembled onto the appropriate insulating member 24 or 25, the screw 10 45 and threaded shell being omitted temporarily. The stamping 62, pawl 64, pawl spring 68, and chain 72 are also assembled as a unitary operating device, the horn being carried on the chain. The spring 76 and 15 shaft 51 are mounted in the insulating member 25, and then the operating device is placed in position with the spring behind the hook 80, after which the spring is tensioned and the horn slipped into place. 20 While the spring is held under tension, the washer 82 and movable contact 52 are slipped onto the shaft with the pawl on the ratchet wheel, and then the two insulating elements are brought together as indicated 25 in Figure 10, the shaft 51 entering the hole 49 in the element 24. The hold on the chain is relieved and the spring moves the parts so that the large ball 72' on the chain is stopped in the horn 83. The parts may be 30 fastened together in a simple manner by passing a long screw 96 through the base of the threaded socket 22, a hole 97 in the member 24, and threading it into a nut 98 on top of the structure, and by threading the screw 35 45 through the socket base, an aperture 99 in the end of the insulating member 24 and into the connecting strip 42.

The switch is operated by the pull chain. One pull operates the member 62 and parts 40 carried thereby so that the pawl 64 turns the ratchet wheel and contact a quarter revolution, whereupon the spring 76 urges the offset portions 55 and 56 into the concaved areas 34-35 or 34'-35', as the case may be. 45 Releasing the pull chain permits the spring 76 to restore the operating parts to position.

It will be noted that the contacts of the present switch may be made large and rugged, and are deeply mounted in the porcelain. The shape of the contacts is such that there is formed a small horn gap at the time of breaking the circuit, and this diminishes 50 55 sparking. The rubbing action of the wiping surfaces keeps the contacts clean.

It is obvious that the invention may be embodied in many forms and constructions, and I wish it to be understood that the particular form shown is only one of the many forms. Various modifications and changes 60 being possible, I do not limit myself in any way with respect thereto.

What is claimed is:

1. An electric switch having a shaft, a pair of fixed contacts, a movable contact in 65 the form of a U-shaped bridging member,

having the ends thereof outwardly directed and cooperable with the fixed contacts, an insulating ratchet wheel attached to the bottom of the U and rotatably mounted on the shaft, an operating device for the bridging member, said device being pivotally mounted on the shaft adjacent the ratchet wheel and being in the form of a substantially flat sheet metal stamping or body, one margin of the sheet being bent at right angles and folded 70 to provide a spaced bearing portion, a pawl mounted between the bearing portion and the body of the stamping, a spring urging the free end of the pawl toward the ratchet wheel, and a spring means for biasing the 75 operating device to predetermined position.

2. An electric switch having a shaft, a pair of fixed contacts, a movable contact in the form of a U-shaped bridging member having the ends thereof outwardly directed and cooperable with the fixed contacts, an insulating ratchet wheel attached to the bottom of the U and rotatably mounted on the shaft, an operating device for the bridging member, said device being pivotally mounted on the shaft adjacent the ratchet wheel and being in the form of a substantially flat sheet metal stamping or body, one margin of the sheet being bent at right angles and folded 80 to provide a spaced bearing portion, a pawl mounted between the bearing portion and the body of the stamping, a spring urging the free end of the pawl toward the ratchet wheel, and a spring means for biasing the 85 operating device to predetermined position.

3. An electric switch having a shaft, a pair of fixed contacts, a movable contact in the form of a U-shaped bridging member having the ends thereof outwardly directed and cooperable with the fixed contacts, an insulating ratchet wheel attached to the bottom of the U and rotatably mounted on the shaft, an operating device for the bridging member, said device being pivotally mounted on the shaft adjacent the ratchet wheel and being in the form of a substantially flat sheet metal stamping or body, one margin of the sheet being bent at right angles and folded 90 to provide a spaced bearing portion, a pawl mounted between the bearing portion and the body of the stamping, a spring urging the free end of the pawl toward the ratchet wheel, and means for rocking the operating device said means including a spring for 95 biasing the operating device to predetermined position.

3. A pull chain electric switch having a shaft, a pair of fixed contacts, a movable contact in the form of a U-shaped bridging member having the ends thereof outwardly directed and cooperable with the fixed contacts, an insulating ratchet wheel attached to the bottom of the U and rotatably mounted on the shaft, an operating device for the bridging member, said device being pivotally mounted on the shaft adjacent the ratchet wheel and being in the form of a substantially flat sheet metal stamping or body, one margin of the sheet being bent at right 105 angles and folded to provide a spaced bearing portion, peripherally disposed elements for attaching and guiding a pull chain, a pawl mounted between the bearing portion and the body of the stamping, a spring urging the free end of the pawl toward the ratchet wheel, a pull chain mounted in said 110 elements, and a spring means for biasing the operating device to predetermined position.

4. An electric switch having a shaft, a pair of fixed contacts, a movable contact in the form of a U-shaped bridging member having the ends thereof outwardly directed and cooperable with the fixed contacts, an insulating ratchet wheel attached to the bottom 115 120 125 130

of the **U** and rotatably mounted on the shaft, an operating device for the bridging member, said device being pivotally mounted on the shaft adjacent the ratchet wheel and 5 being in the form of a substantially flat sheet metal stamping or body, one margin of the sheet being bent at right angles and folded to provide a spaced bearing portion, a pawl mounted between the bearing portion and 10 the body of the stamping, a spring urging the free end of the pawl toward the ratchet wheel, and a spring coiled about the shaft and having one end fixed and one end attached to the operating device, said spring 15 restoring the device to a predetermined angular position and urging the movable contact against the fixed contacts.

5. An electric switch having an insulating structure comprising two elements each having a disk-like end wall and a prismatic portion extending from one side of the end wall, the inner faces of said portion being recessed to accommodate switch mechanism, the end wall of one element fitting the end 20 of the prismatic portion of the other element thereby forming an enclosing chamber, means for fastening the two elements together, a shaft supported by said elements transverse of said chamber, a pair of fixed 25 contacts carried on the inside of one element, a movable contact in the form of a **U**-shaped bridging member having the ends thereof outwardly directed and cooperable with the fixed contacts, an insulating ratchet wheel 30 attached to the bottom of the **U** and rotatably mounted on the shaft, an operating device for the bridging member, said device being pivotally mounted on the shaft adjacent the ratchet wheel and being in the form 35 of a substantially flat sheet metal stamping or body, one margin of the sheet being bent at right angles and folded to provide a spaced bearing portion, a pawl mounted between the bearing portion and the body of the stamping, a spring urging the free end of the pawl toward the ratchet wheel, a pull chain 40 mounted in said elements, a spring means for biasing the operating device to predetermined position, and external connectors for the fixed contacts. 45

40 5. A pull chain electric switch having an insulating structure comprising two elements each having a disk-like end wall and a prismatic portion extending from one side of the

end wall, the inner faces of said portion being recessed to accommodate switch mechanism, the end wall of one element fitting the end of the prismatic portion of the other element thereby forming an enclosing chamber, means for fastening the two elements together, a shaft supported by said elements 55 transverse of said chamber, a pair of fixed contacts, a movable contact in the form of a **U**-shaped bridging member having the ends thereof outwardly directed and cooperable with the fixed contacts, an insulating ratchet 60 wheel attached to the bottom of the **U** and rotatably mounted on the shaft, an operating device for the bridging member, said device being pivotally mounted on the shaft adjacent the ratchet wheel and being in the form 65 of a substantially flat sheet metal stamping or body, one margin of the sheet being bent at right angles and folded to provide a spaced bearing portion, peripherally disposed elements for attaching and guiding a 70 pull chain, a pawl mounted between the bearing portion and the body of the stamping, a spring urging the free end of the pawl toward the ratchet wheel, a pull chain mounted in said elements, a spring means 75 for biasing the operating device to predetermined position, and external connectors for the fixed contacts.

7. In an electric switch, a movable contact in the form of a **U**-shaped bridging member having the ends thereof outwardly directed, and having a centrally disposed hole in the bottom of the **U**, there being 80 prongs projecting from the bottom of the **U**, and an insulating ratchet wheel attached to the prongs and having an axially disposed aperture of smaller diameter than the hole in the bridging member.

8. In an electric switch, a movable contact in the form of a **U**-shaped bridging member 85 having the ends thereof outwardly directed, and provided with obliquely disposed wiping surfaces, and having a centrally disposed hole in the bottom of the **U**, there being prongs projecting from the bottom of the **U**, and an insulating ratchet wheel attached to 90 the prongs and having an axially disposed aperture of smaller diameter than the hole 100 in the bridging member.

ELIAS RATNER.
